UNITED STATES PATENT OFFICE.

FRANKLIN W. OEHRLIE, OF PHILADELPHIA, PENNSYLVANIA, ASSIGNOR TO OEHRLIE BROTHERS COMPANY, OF PHILADELPHIA, PENNSYLVANIA, A CORPORATION OF PENNSYLVANIA.

DESIGN FOR A FRINGE.

Application filed January 26, 1922. Serial No. 379. Term of patent 3½ years.

To all whom it may concern:

Be it known that I, FRANKLIN W. OEHRLIE, a citizen of the United States, residing in Philadelphia, in the county of Philadelphia and State of Pennsylvania, have invented a new, original, and ornamental Design for Fringe, of which the following is a specification, reference being had to the accompanying drawing, forming part thereof.

In the drawing:

Fig. 1 is a view of the front side; and
Fig. 2 a view of the rear side of a piece of fringe showing my new design.

I claim:

The ornamental design for fringe, as shown.

In testimony whereof I have hereunto signed my name this 23d day of January, A. D., 1922.

FRANKLIN W. OEHRLIE.
